UNITED STATES PATENT OFFICE

EDWARD J. WEITZEL, OF BROOKLYN, NEW YORK, ASSIGNOR TO ROLLING SCREENS, INC.,
OF BROOKLYN, NEW YORK, A CORPORATION OF NEW YORK

CORNER BRACE FOR WINDOW SCREENS

Application filed June 26, 1931. Serial No. 546,940.

The invention relates to metal frames for window and door screens, and more particularly to corner braces of the tubular type of frames and utilized for connecting the frame elements together.

The invention has for an object to so secure the said frame elements together at the corners as to afford a rigid joint thereat and, also, in such a manner that no soldering, brazing or welding is required in the assembly.

A further object of the invention resides in a right-angled corner brace member having arms adapted to receive and lock thereto the frame elements, the said brace member being provided, also, with means to lock therein the screen spline, and the novel arrangement assuring, moreover, strength and rigidity to the corners of the frame.

Another object of the invention resides in the provision of fingers or tongues extending from the brace member and adapted to spread the ends of a fastening spline for the screen, and prevent also the tubular frame from spreading at the ends and tending to get out of shape when forced over the arms of the brace member.

It has been the general practice in the construction of metallic tubular screen frames to solder, braze or weld the corners thereof to the frame elements, and it is found that the use of acid and chemicals in such soldering and brazing operations tends to rust or corrode the inside of the tubular frame elements, especially at said corners. This causes the frames to be relatively weak and frail at this particular portion and consequently frames thus constructed do not retain their original shape when in use.

By means of the novel corner brace herein-after more fully described, a particularly rigid corner construction is attained having the frame elements positively held thereto without any soldering, brazing or welding thereof.

The nature of the invention, however, will best be understood when described in connection with the accompanying drawings, in which:

Figs. 1 and 2 are perspective views of the novel corner brace adapted to receive the cor-

responding frame elements for attachment thereto.

Fig. 3 is an end elevation thereof.

Fig. 4 is a fragmentary front elevation of a corner of a metal screen with its frame elements secured by the novel corner brace. 55

Fig. 5 is a fragmentary transverse section taken on the line 5-5, Fig. 4.

Referring to the drawings, 10 designates the body portion of a corner brace member 60 having diverging therefrom the arms 11 and 12 which are integral therewith and located to extend at right angles to each other. These arms are adapted to receive, respectively, the corresponding frame elements or 65 hollow rails 13 and 14 which are in the nature of a rectangular tube, Fig. 5, formed preferably from a single piece of metal and provided along an inner edge with a channel 15. The edges of the screen cloth 16 are deflected 70 into this channel and retained therein by so-called molding strips or splines 17, all of which is more particularly set forth in U. S. Letters Patent No. 1,732,628. As stated, the arms 11 and 12 are designed to enter the ends 75 of corresponding horizontal and vertical rails; and said arms are reduced in size or depressed slightly below the surface of the body portion to provide shoulders 18 and 19 affording abutments for limiting the inward 80 position of a rail on its arm.

In order to secure a rail fixedly to its arm, the latter may be provided along its outer edge with depressions 20 which are formed in cross-pieces or studs 21 of the more or less channel-shaped arms, and the top of a rail is correspondingly forced or drawn into the said depressions to form tubular studs 22 which will serve to lock a rail thereby securely and rigidly to an arm, the two rails 90 being thus held in squared relationship to each other. No soldering, brazing or welding is required in thus securing a rail to the corner member, the ends of the rail abutting the respective shoulders 18 and 19 and the 95 top of the rail lying substantially flush with the body portion 10, as indicated in Fig. 4.

Depressions 23 and 24 may be provided in the top and side respectively of the body portion in which identification numbers may be 100

stamped and which will be hidden when the screen is in use and thus will not disfigure the face of the screen.

In accordance with the invention, a pair 5 of fingers 30 and 31 displaced from the corresponding arms are arranged to extend a short distance from the inner corner of the body portion and substantially parallel to the respective arms 11 and 12. These fingers, 10 furthermore, are designed to enter the channel 15 of a rail to spread the fastening ends of the holding spline when the same is inserted in place to secure the wire screen to the frame. This affords, also, a better se- 15 curing of the screen at the immediate corner than in constructions where the fastening spline is left the same width throughout its entire length.

The said fingers, furthermore, assure ab- 20 solute alignment of a rail at the adjacent ends of each pair of the rails to produce always a smooth and flat surface at this point, as well as affording a reinforcement for the spline channel and support for the ends of 25 a fastening spline.

When placing a rail over an arm 11 or 12, the bottom wall of the tubular rail will engage with the corresponding edge of a finger and prevent the tube from spreading at its 30 ends so that a smooth and finished appearance of the corner connection is attained. Moreover, the inner edge of the lower wall of a channel is intended to abut a corresponding wall of a right-angled projection 32 formed at the inner corner of the two fingers 35 for the cooperating rails and present a finished appearance of said rails by thus securing an edge fit therebetween.

I claim:

40 1. In a screen frame construction: a pair of tubular rails, a metal corner brace member comprising a body portion having two arms extending therefrom at right angles to each other to receive respectively said tubular rails, the said tubular rails being provided with inner channels for securing therein screen material, and two fingers displaced from the respective arms extending outwardly from the inner corner of the body portion 45 substantially parallel to the said arms and adapted to fit within the channels of the respective rails when the arms are inserted in the ends of the tubular rails.

50 2. In a screen frame construction: a pair of tubular rails, a metal corner brace member comprising a body portion having two arms extending therefrom at right angles to each other and depressed slightly below the surface of the body portion to afford abut- 55 ment shoulders respectively for the ends of said tubular rails, the said tubular rails being provided with inner channels for securing therein screen material, and two fingers displaced from the respective arms extending 60 outwardly from the inner corner of the body 65

portion substantially parallel to the said arms and adapted to fit within the channels of the respective rails when the arms are inserted in the ends of the tubular rails.

70 3. In a screen frame construction: a pair of tubular rails, a metal corner brace member comprising a body portion having two arms extending therefrom at right angles to each other to receive respectively said tubular rails, the said tubular rails being provided with inner channels for securing therein screen material, two fingers displaced from the respective arms extending outwardly from the inner corner of the body portion substantially parallel to the said arms and adapted to fit within the channels of the respective rails when the arms are inserted in the ends of the tubular rails, and a right-angled projection at the inner corner of the fingers affording a stop for the inner ends 80 of the lower wall of the channels.

75 4. In a screen frame construction: a pair of tubular rails, a metal corner brace member comprising a body portion having two arms extending therefrom at right angles to each other to receive respectively said tubular rails, the said tubular rails being provided with inner channels for securing therein screen material, and the outer edges of the arms being provided with locking depre- 90 sions to receive projections of the rails.

85 In testimony whereof I affix my signature.
EDWARD J. WEITZEL.
